UNITED STATES PATENT OFFICE

GEORGE GILL, OF TAUNTON, MASSACHUSETTS, ASSIGNOR TO REED & BARTON, OF SAME PLACE.

DESIGN FOR A CAKE-BASKET.

Specification forming part of Design No. 6,379, dated February 4, 1873.

To all whom it may concern:

Be it known that I, GEORGE GILL, of Taunton, in the county of Bristol and State of Massachusetts, have invented a new and original Design for Cake-Baskets; and I do hereby declare the following to be a full, clear, and exact description of the same, reference being had to the accompanying drawing forming a part of this specification.

The invention consists in a new and ornamental design for the shape and configuration of cake-baskets and analogous articles, as hereinafter fully described.

Figure 1 is a side elevation, and Fig. 2 is a top view.

A represents the bail, made nearly rectangular. The body consists of a curved plate, B, and two side flanges, C C, at right angles thereto. The faces of the plate B and flanges

C C may be engraved or ornamented in any suitable manner. The stand has a solid curved plate, D, gradually diminishing to the projection d and resting on ornamented feet at each of four corners.

Having thus described my invention, what I claim as new, and desire to secure by Letters Patent, is—

1. The general design for the whole cake-basket, as shown and described.
2. The design for body, as shown and described.
3. The design for stand, as shown and described.

GEORGE GILL.
